UNITED STATES PATENT OFFICE.

VICTOR POPP, OF PARIS, FRANCE.

DEVICE FOR WINDING UP COUNTER-WEIGHTS.

SPECIFICATION forming part of Letters Patent No. 358,623, dated March 1, 1887.

Application filed September 29, 1886. Serial No. 214,844. (No model.) Patented in France January 30, 1886, No. 173,863; in Belgium June 22, 1886, No. 73,572, and in England June 29, 1886, No. 8,530.

To all whom it may concern:

Be it known that I, VICTOR POPP, of the city of Paris, France, have invented a new and useful Device for Automatically Winding 5 up Counter-Weights by Means of Fluid, Gas, or other Pressure, of which the following is a full, clear, and exact description.

This invention consists of a system of automatically winding up counter-weights for 10 transmitting or accumulating power, based on the employment of a fluid, liquid, vapor, or gas under a constant or variable pressure acting on the elements, which I shall describe farther on, and which I have shown on the 15 appended drawings, but solely as an illustration.

In the drawings, Figure 1 shows a complete view of my system of automatically winding up counter-weights as applied to the motive 20 part of a Hughes telegraph, the upper wheel being the driving-wheel of the mechanism of said Hughes telegraph. Fig. 2 is a detail drawing, showing a front elevation, in partial section, of the devices for distributing the compressed fluid.

In the figures the same letters refer to the same parts.

My apparatus comprises two principal parts: first, a cylinder, A, in which works a piston, 30 B, which is acted upon on one side only by the pressure of the fluid, the other side being open to the atmosphere; second, a three-way cock, R, for distributing the compressed fluid to the cylinder A and for exhausting the same 35 fluid when the end of it has acted on the piston B. The handle of the cock is furnished with a hollow cross-bar, T, which is filled to about one-third of its interior volume with mercury. This cross-bar opens or closes the 40 cock at the desired moment. This being premised, the operation of the apparatus is as follows:

The weight P, acting on the elements which it has to set in motion, descends under the influence of its own weight. The two parts C 45 C of the chain descend with it, while the parts D D of the same chain ascend, lifting the counter-weight E, the sheave F, and the block G, fixed on that sheave. This block G, in the 50 form of an extended ring, incloses one of the ends of the cross-bar T. When the weight P

has nearly arrived at the ends of its course, the block G in its upward movement lifts the cross-bar T. The mercury inside is gradually displaced by the lifting of the cross-bar, and 55 when the latter has reached a point a little beyond the horizontal it (the cross-bar) is operated by the weight of the mercury, which has all gone over to the other end of the cross-bar. At this moment the cock is opened to its 60 whole extent. The fluid under pressure, supplied through the pipe M, connecting with a receiver for compressed air or other compressed fluid, water, steam, &c., or with a compressing-pump, passes through the pipe N into the cylinder A and acts on the piston B, forcing it to the other end of the cylinder. By means of the rod H and a chain, I, the motion of the piston is transmitted to a disk, O, keyed on the shaft which carries the return-sheave of the parts C 65 and D of the chain supporting the weight P. The weight is thus brought back (wound up) into its normal position; but while the weight P is being wound up the block G descends, and when the weight P is at the end of its course 70 pulls the cross-bar T of the cock back in the opposite direction to its first movement. The mercury again exerts its tilting action and places the cross-bar in the position shown in dotted lines on the drawings, Fig. 2. At this 75 moment the inlet-opening of the cock is closed and the escape-pipe L is put in communication with the cylinder A, so as to afford an outlet for the fluid after it has acted on the piston.

When the weight P has gone down again, the same operations are repeated, so that the winding up of the weight takes place automatically and alternately.

V is a spring serving to bring back the piston to the front end of the cylinder. This spring may be of any shape, and may be replaced either by the admission of the fluid to the other side of the piston or by the employment of another cylinder with its piston.

The winding up of the weight by means of electricity may be effected by changing the cock R into a commutator, which, according to the different positions it may take, Fig. 2, would establish or break an electrical circuit.

I claim—

1. The combination of the cylinder provided

with a piston, conduits N and L, the three-way cock having the hollow cross-bar, the block G, the wheel or disk F, the chain C D, the pulleys over which said chain works, and 5 the counter-weight P, substantially as and for the purpose set forth.

2. The cock R, in combination with a hollow cross-bar, T, filled about one-third with a heavy liquid, the tilting movement of this cross-bar operating this cock, as described and illustrated.

3. The combination of the cylinder A, provided with a piston, B, conduits N and L, the three-way cock R, having a hollow cross-bar,

T, the block G, the wheel or disk F, the chain 15 C D, the counter-weight P, a number of pulleys or wheels, and a spring connected to the piston through its piston-rod and a chain passed over one of said pulleys, substantially as and for the purpose set forth.

The foregoing specification of my method of winding up automatically counter-weights for transmitting or accumulating power signed by me this 10th day of September, 1886.

VICTOR POPP.
